UNITED STATES PATENT OFFICE.

ERNEST WILLOUGHBY GATES, OF WRENTHAM, MASSACHUSETTS.

PUZZLE OR GAME.

Application filed May 21, 1926. Serial No. 110,650.

The object of this invention is to provide a puzzle symbolizing a broadcasting radio station, a receiving radio station, the phenomenon known as "static", and signals transmitted from the broadcasting station to the receiving station, the feat to be accomplished being the transmission of the signals through static to the receiving station, and the spelling of a call at the latter.

10 I attain this object by the improved puzzle hereinafter described and claimed.

Of the accompanying drawings forming a part of this specification,—

15 Figure 1 is a plan view of a puzzle embodying the invention, as prepared for use.

Figure 2 is a fragmentary plan view, showing the portion symbolizing the receiving station, and showing a call partly spelled.

20 Figure 3 is a fragmentary section on line 3—3 of Figures 1 and 2.

Figure 4 is a fragmentary section on line 4—4 of Figures 1 and 2.

25 Figure 5 is a fragmentary perspective view, showing a portion of the base and one of the pockets and sight openings hereinafter described.

Figure 6 is a perspective view, showing one of the annunciator members hereinafter described.

30 Figure 7 is a fragmentary section on line 7—7 of Figure 1.

Figure 8 is a fragmentary section on line 8—8 of Figure 1.

35 The same reference characters indicate the same parts in all of the figures.

The puzzle comprises a base adapted to be held at various inclinations by the hands of a user, and to permit the rolling on its 40 upper surface of rolling members which may be either balls or discs, balls being preferred. For brevity I hereinafter refer to the rolling members as balls.

The base may be of any desired construction, and, as here shown, includes a body portion 12, and a facing portion 13 on which the balls may roll. The base is provided with an upstanding marginal curb 14, confining the balls on the base. The curb may 50 be provided with a glass cover 15, as shown by Figures 3 and 4. At one end portion of the base is a depression 16, symbolizing a broadcasting station, and at the opposite end portion of the base is a group of pockets 17 which, with the annunciator members hereinafter described, symbolize a receiving sta-

tion. The base is provided, intermediate the depression 16 and pockets 17, with a group of baffle members 18, symbolizing "static".

50 The puzzle comprises also a set of balls 19, the number of which is the same as that of the pockets 17, said balls symbolizing signals. The balls are adapted to be loosely confined by the depression 16, as shown by Figures 1 and 8, when the base is horizontal, and to roll from the depression toward the pockets, when the base is suitably inclined.

55 With the pockets 17 are associated inscribed annunciator members constituting a group corresponding in number with the pockets, each annunciator member being normally inoperative or concealed, and movable to an operative or displayed position, displaying its inscription, by a ball 19 arrested by a pocket 17. The inscriptions on the annunciator members are letters, as indicated by Figures 2 and 6, and the arrangement is such that when the several balls are arrested by the several pockets, the displayed 60 annunciator members spell a call.

65 In the preferred embodiment of the invention here shown, each annunciator member is composed of a two-armed lever 21, fulcrumed at 22 (Figures 3 and 4), adjacent to a pocket 17. The outer arm of the lever is enlarged to form a target 23, bearing an inscription. The inner arm projects into the pocket and is normally raised therein, as shown by Figure 3, by the outer 70 arm. When a ball 19 is arrested by the pocket, it depresses the inner arm and raises the target 23, as shown by Figure 4, so that the target is displayed through a sight opening 24, in the base. The lever 21 may 75 extend through a slot 25, in the base (Figures 3, 4 and 5) to a chamber 26, in which the target is movable.

80 The baffle members 18 are preferably arranged in a plurality of rows extending across the base, as shown by Figure 1, the rows being interrupted by staggered passages 27, through which the balls are adapted to roll, the arrangement of the passages being such that the balls cannot roll in a straight course from the depression 16 to the pockets 17. The feat to be accomplished is to cause the balls to roll through the staggered passages 27, and be landed in the pockets 17, each ball being landed in a 85 pocket, and the several annunciator members 90 being displayed and caused to spell a call.

The accomplishment of this feat is rendered difficult by the baffle members, as will be readily seen.

The base may be provided with markings 5 representing an antenna 28, associated with the depression 16, and an antenna 29, associated with the pocket 17. Zigzag markings 30 may appear between the rows of baffle members 18.

10 I claim:

1. A symbolic puzzle comprising a base having a depression at one end portion, symbolizing a broadcasting station, a group of pockets at the opposite end portion, and 15 an intermediate group of baffle members symbolizing static; a set of loose rolling members symbolizing radio signals and adapted to be confined by the depression when the base is horizontal and to roll therefrom toward the pockets when the base is inclined, the number of rolling members being equal to that of the pockets, each pocket being adapted to arrest a rolling member, the baffle members being arranged to deflect 20 the rolling members from a straight course between the depression and the cups; and a group of inscribed annunciator members associated with the pockets, each annunciator member being normally inoperative and 25 movable to an operative position displaying

its inscription by a rolling member arrested by a pocket, the pockets and the annunciator members symbolizing a radio receiving station, the arrangement being such that when the several rolling members are arrested by the several pockets, the displayed annunciator members spell a call. 35

2. A symbolic puzzle as specified by claim 1, the baffle members being arranged in a plurality of rows extending crosswise of the base, the rows being interrupted by staggered passages for the rolling members, so arranged that said members cannot roll in a straight course from the depression to the pockets. 40

3. A symbolic puzzle as specified by claim 1, each annunciator member being composed of a two-armed lever fulcrumed adjacent to a pocket, one arm of the lever being enlarged to form a target, the other arm being normally raised in the pocket, so that it may be depressed by a rolling member arrested by the pocket, and thereby caused to raise the target, the base being provided with sight openings through which the raised targets are visible. 50

In testimony whereof I have affixed my signature.

ERNEST WILLOUGHBY GATES. 55
